**(54) THRASHING & WINNOWING
MACHINS/THRA**

(76) Inventor: Lawrence Hock

The Schedule referred to in these Letters Patent
is made a part of the same, containing a description
in the words of the said Lawrence Rock him-
self of his Threshing and Winnowing machine.

This invention consists of the Threshing
Machine or Mill, the Winnowing Pan, and the
frame or carriage.

The Threshing Machine which forms the principal
part of this invention may be divided into
two parts: the feeder, and the threshing mill.
The feeder is a stage of such height as to carry
the grain in the straw horizontally to the threshing
mill. This is effected by two rollers which
press the straw to a roller and carried onward
a wooden rock wheel is placed at one of the rollers,
which is moved by a hand in the same manner
as the carriage when the said mill is propelled.
The straw or grain in the straw being forced on
this roller passes to the threshing mill regularly
so as to give a uniform supply.

The threshing mill which will be as
described the chief part of the invention
is a combination for rubbing the grain from the
straw by passing it between two serrated or toothed
surfaces. These may be either horizontal or perpendicular
to, or forming the part of a circle, or a curve. The
surfaces to make frame this my invention.
I proceed to describe a threshing mill, the
one which is part of a circle. In this case, about
the circle of the frame of a circle will answer well.

having the upper edge of the lower floor, or fixed part of the mill on or about the same level with the thrashing cloth. The width of the mill about the same width of the feeder and sufficient to take the grain out either way. The bottom, or floor of the mill, which are placed on the arc of a circle is of wood or metal, and fluted or serrated transversely, with the sharp edges of the teeth, ribs, or spikes downwards. The chamber, or upper and moving part of this machine comes much corresponding with that of the floor, and is acted in the same manner, and may be made either of wood, metal, or other brittle materials. It may be divided in the middle, and then connected by hinges, so that when the upper part rises above the feeder it may fall back to receive the grain and straw from the feeder. On the upper side of each side of this moving back is it turns on a centre within a frame, so as to be moved about the angle of the floor by a jibboom which directs from an arm, or bar, above. Hence it will be seen, that as the jib is raised or lowered the upper chamber is carried along the circle or sweep of the thrashing floor, and the grain when it is raised up. On the upper edge of the moving of this back, there may be placed parallel and horizontal knives, which cut the bunches of the sheaves as they enter the mill. After the grain has been raised from the back, chaff or straw, it descends into the floor of the mill, falling over the lower edge from a ridge which separates the straw and admits the grain to fall upon a fluted hopper; from this hopper it passes through an aperture, and as it descends receives the blast of wind from the flyers of the winnowing fan. The chaff being

thus separated, the "clean" parts on a screen where the impurities, Clark, and small ("fououl") passed from the clean drain.

The winnowing air has four or more vertical vanes, revolving horizontally, being raised & kept at the top, and the air being expelled through an horizontal aperture to the grain as it descends from the hopper. To give motion to this machine, have a horse wheel placed within the frame of the carriage. The toothed horizontal wheel of which works in the wallower of our horizontal shaft; on the other end of which is placed a spur wheel which turns the turntable board on a upright shaft, in the flyers or fan. The same horizontal shaft has at its centre end, a crank wheel by a vertical pinion, which the axis which carries the pinions of the movable flywheel, and also the hand which drives the notched wheel of the feeder.

The carriage or frame which contains this machine, will be placed on tracks or wheels by which it can be drawn from place to place where wanted.
